VAPORIZER UNIT

Roy Robert Fisher, Paris, Ky., assignor to Electric Steam
Radiator Corporation, Paris, Ky., a corporation of Kentucky

Application October 12, 1954, Serial No. 32,637

Term of patent 14 years

(Cl. D83—1)

The figure is a perspective view of a vaporizer unit showing my new design.

The undisclosed side of the device is similar to and symmetrical with the side which is exposed in the drawing.

I claim:

The ornamental design for a vaporizer unit, as shown and described.
